BOTTLE CLOSURE

Charles A. Schultz, New York, N.Y., assignor, by direct and mesne assignments, to Lok-Seal, Inc., New York, N.Y., a corporation of New York

Filed Nov. 17, 1958, Ser. No. 774,193

10 Claims. (Cl. 215—48)

The present invention relates to a bottle closure, and more particularly to a bottle closure for champagne and wine beverages, having a three-part construction that is readily fabricated and easily inserted into the neck of a bottle and locked thereon.

Champagne and other wines are universally sold in glass bottles that have the necks thereof closed by cork stoppers. These cork stoppers are made from a high grade of natural cork. The corks used in present day practice are initially substantially larger than the interior diameter of the bottle necks, and they are compressed greatly in order that they may be reduced to such a size that they may be inserted into the neck of the bottle. The corks extend a substantial distance into the bottle neck, and because of their tendency to resume their original size, they exert a substantially great expansive force against the interior of the bottle neck. This effects the necessary seal so that neither gas nor liquid may pass out of the bottle.

The compression of the corks and their insertion into the bottle necks is an expensive operation. It is accomplished most rapidly and most economically at the present time by machinery that is only semi-automatic, so that a relatively large amount of manpower is required to insert the corks into the bottle necks.

After the corks have been thus inserted, it is the universal practice to insure their retention in the bottle, against the internal pressure of the gases within the bottle, by a wire anchor. The placing of the wire anchor on the cork and the securing of it to the neck of the bottle is another expensive operation. Here again, the best and most efficient equipment available is only semi-automatic, and accordingly considerable manpower is required to place the wire anchors on the bottles.

As expensive, laborious and time-consuming as the above operation is, it is universally used for the bottling of champagne and is the most used sealing arrangement for other types of wine. This is true despite the fact that workers in the art have produced bottle closures made of other materials and having substantially different characteristics from the cork and wire closure above described. It may therefore be seen that the efforts of the prior workers in the art have been rejected.

The rejection of prior art bottle closures intended to substitute for the cork and wire closure has been because these closures were either made of expensive material, or were expensive to fabricate, or did not lead to any economical advantages by their use, or did not provide for a truly secure seal. Another reason for the rejection for the prior closures was that they were difficult to manipulate, either during the sealing operation, or during the opening operation.

It is an object of the present invention to provide a closure for bottles of champagne and similar beverages that is made of readily available material, and is easily and economically fabricated.

Another object of the present invention is the provision of a closure for champagne bottles and the like that may

2

be inserted into the necks of bottles by an economical operation.

A still further object of the present invention is to provide a closure that will insure the sealing of the bottle.

Yet another object of the present invention is the provision of a closure that may be readily secured to and removed from the neck of a bottle.

Other objects and the nature and advantages of the instant invention will be apparent from the following description taken in conjunction with the accompanying drawings, wherein:

Fig. 1 is an elevational view of the neck of a bottle having the closure of the present invention mounted thereon.

Fig. 2 is a cross-sectional view taken on the line 2—2 of Fig. 1.

Fig. 3 is a cross-sectional view taken on the line 3—3 of Fig. 2.

Referring now to the drawings, wherein like reference numerals are used to designate like or corresponding parts throughout the several views, there is shown in Fig. 1 the neck 10 of a bottle having the closure 20 of the present invention inserted and secured thereto. As may be seen from Fig. 2, closure 20 comprises a stopper 21 that is made of polyethylene. Polyethylene is a relatively soft and resilient plastic that is readily available, and may be easily molded. The stopper 21 has a hollow axial extension 22 that has a plurality of ribs 23 on the exterior thereof. The ribs 23 are shown partially flattened in Fig. 2, since they have compressed during the insertion of the stopper 20 into the neck 10. At the upper end of the extension 22 is an outstanding annular flange 24. The under side of the flange 24 is in surface contact with the lip 11 of the neck 10. Above the flange 24 is a relatively thick walled, hollow crown 26.

A known securing member 30 forms a part of the closure of the present invention, the member 30 comprising a metal cap having a top 31 with a central hole 32 therein through which the crown 26 extends. A peripheral side wall 33 depends from the top 31 and extends downwardly past the flange 24. The side wall 33 is furcated, at its lower part, as may be seen in Fig. 1, and the furcations 34 thus formed are curled as shown at 35. A fastening wire 36 extends through the curled parts 35, and is held thereby. A lever 37 is pivotally attached to the ends of the wire 36, and in known manner may be rotated from the position shown through approximately 180°. During this rotation, the wire 36 may have its ends drawn closer together, or permitted to spread further apart, to thereby reduce or enlarge the diameter of the wire 36. This will lock or release the closure, as the case may be, under the bead 12 at the top of the neck 10. The securing member 30 is known per se, and its construction and operation are therefore not set forth in detail.

A head 40 is provided to afford a handy gripping member to aid in extracting the closure from the neck of the bottle. The head 40 is of polystyrene and comprises an annular gripping member 41 having a shoulder 42 at the lower end thereof in engagement with the upper surface of the top 31 of the metal cap. Annular gripping member 41 has an interior wall 43 (see Fig. 3), and a plurality of teeth 44 extend inwardly from the interior wall 43. The crown 26 of the stopper 21 extends upwardly into the bore defined by the interior wall 43, and the hard polystyrene teeth 44 extend into the soft polyethylene crown 26. It will be observed from Fig. 2 that the teeth 44 have their lower surfaces upwardly slanted, and their top surfaces substantially horizontal. A dome 46 rises from the gripping member 41 and covers over the upper end of the head 40. Holes 47 are provided

so that during assembly no air will be trapped between the head 40 and stopper 21.

The closure of the present invention is so constructed as to be readily fabricated. The molding of the polyethylene stopper 21 and the polystyrene head 40 may be readily, rapidly and economically achieved by the use of relatively standard production techniques. Similarly, the metal cap may be economically produced. Once the three separate parts of the closure 20 have been made, they may be assembled in large numbers at low cost, the assembly operation being simply the lowering of the cap over the crown 26 of the stopper 21, and then the driving of the head 40 over the crown 26. The slanted lower faces of the teeth 40 will permit relative longitudinal movement of the head 40 into assembled position on the crown 26 of the stopper 21; after the head 40 is in place, the upper flat or horizontal face of the teeth 44 will prevent withdrawal of the head 40 from the stopper 21, since the teeth 44 will be embedded in the crown 26.

Once the stopper 20 has been thus assembled, it is ready for placement in the neck of a bottle. The lever 37 is moved to the position in which the fastening wire 36 has the greatest diameter, and the hollow axial extension 22 is then driven down into the neck 10 of a bottle. Because of the relatively long axial extent of the extension 22, and because of the ribs 23, there is substantial sealing engagement of the stopper 21 with the interior of the neck 10 of the bottle. This provides and insures a seal, so that every bottle on which the closure of the present invention is used is positively and securely sealed. After the closure 20 has been driven home so that the flange 24 rests on the lip 11 of the neck of the bottle, the lever 37 is rotated into its locking position and thus the diameter of the fastening wire 36 is reduced and the metal securing member 30 is then firmly attached to the bottle. Removal of the closure 20 from a bottle by the ultimate purchaser is both simple and easy. The lever is simply moved from the locking position to the release position. This causes the securing member 30 to become inactive. By pushing upwardly with the thumb on the gripping member 41, and aided by the pressure within the bottle, the entire closure 20 may be removed from the neck 10 of the bottle, the extension 22 being withdrawn from the neck passage at this time.

There has been provided a closure for champagne and the like beverages that is economically fabricated, both from the standpoint of manufacture of the constituent parts and from the viewpoint of assembly of these parts. The assemblage of the closure of the present invention onto the neck of a bottle may be accomplished with extreme economy, and thus completely eliminates the semi-automatic equipment now in use. The closure of the present invention is easily removed without the use of any special tools or devices.

It will be obvious to those skilled in the art that various changes may be made without departing from the spirit of the invention and therefore the invention is not limited to what is shown in the drawings and described in the specification but only as indicated in the appended claims.

What is claimed is:

1. A closure for the neck of a bottle comprising a polyethylene stopper having an externally ribbed, hollow axial extension, an outstanding annular flange at the upper end of said extension, and a relatively thick-walled, hollow polygonal crown above said flange, a securing member comprising a metal cap having a top, a hole in said top for receiving said crown, a peripherally extending side wall depending from said top and extending downwardly past said flange, said side wall being furcated at its lower part and having curled furcations, a fastening wire in the curls of said furcations, lever means for reducing the diameter of said fastening wire to thereby lock said closure under the bead at the top of the neck of a bottle, and a polystyrene head, said head comprising an annular grip-

ping member having a shoulder at the lower end thereof for engagement with the upper surface of the top of said metal cap and an interior wall of a complementary shape to said polygonal crown, a plurality of teeth extending inwardly from the interior wall of said annular gripping member, said teeth having inwardly and upwardly inclined lower faces and generally horizontal upper faces, said crown extending upwardly into the bore of said gripping member and said teeth being embedded in said crown, and a dome having an air passage therethrough rising from said gripping member and covering over the upper end of said head.

2. A closure for the neck of a bottle comprising a relatively soft stopper having an externally ribbed, hollow axial extension, an outstanding annular flange at the upper end of said extension, and a relatively thick-walled, hollow polygonal crown above said flange, a securing member comprising a metal cap having a top, a hole in said top for receiving said crown, a peripherally extending side wall depending from said top and extending downwardly past said flange, said side wall being furcated at its lower part and having curled furcations, a fastening wire in the curls of said furcations, lever means for reducing the diameter of said fastening wire to thereby lock said closure under the bead at the top of the neck of a bottle, and a relatively hard head, said head comprising an annular gripping member having a shoulder at the lower end thereof for engagement with the upper surface of the top of said metal cap and an interior wall of a complementary shape to said polygonal crown, a plurality of teeth extending inwardly from the interior wall of said annular gripping member, said teeth having inwardly and upwardly inclined lower faces and generally horizontal upper faces, said crown extending upwardly into the bore of said gripping member and said teeth being embedded in said crown, and a dome rising from said gripping member and covering over the upper end of said head.

3. A closure for the neck of a bottle comprising a relatively soft stopper having an externally ribbed, hollow axial extension, an outstanding annular flange at the upper end of said extension, and a relatively thick-walled, hollow polygonal crown above said flange, a securing member comprising a metal cap having a top, a hole in said top for receiving said crown, a peripherally extending side wall depending from said top and extending downwardly past said flange, said side wall being furcated at its lower part and having curled furcations, a fastening wire in the curls of said furcations, lever means for reducing the diameter of said fastening wire to thereby lock said closure under the bead at the top of the neck of a bottle, and a relatively hard head, said head comprising an annular gripping member having a shoulder at the lower end thereof for engagement with the upper surface of the top of said metal cap and an interior wall of a complementary shape to said polygonal crown, a plurality of teeth extending inwardly from the interior wall of said annular gripping member, said teeth having inwardly and upwardly inclined lower faces and generally horizontal upper faces, said crown extending upwardly into the bore of said gripping member and said teeth being embedded in said crown, and a dome rising from said gripping member and covering over the upper end of said head.

4. A closure for the neck of a bottle comprising a relatively soft stopper having a hollow axial extension, an outstanding annular flange at the upper end of said extension, and a relatively thick-walled, hollow polygonal crown above said flange, a securing member comprising a metal cap having a top, a hole in said top for receiving said crown, a peripherally extending side wall depending from said top and extending downwardly past said flange, means for reducing the diameter of the lower part of said side wall to thereby lock said closure under the bead at the top of the neck of a bottle, and a relatively hard head, said head comprising an annular gripping member having a shoulder at the lower end thereof for engagement with the upper surface of the top of said metal cap and

an interior wall of a complementary shape to said polygonal crown, a plurality of teeth extending inwardly from the interior wall of said annular gripping member, said crown extending upwardly into the bore of said gripping member and said teeth being embedded in said crown, and a dome rising from said gripping member and covering over the upper end of said head.

5. A closure for the neck of a bottle comprising a relatively soft stopper having a hollow axial extension, an outstanding annular flange at the upper end of said extension, and a relatively thick-walled, hollow polygonal crown above said flange, a securing member comprising a metal cap having a top, a hole in said top for receiving said crown, a peripherally extending side wall depending from said top and extending downwardly past said flange, means for reducing the diameter of the lower part of said side wall to thereby lock said closure under the bead at the top of the neck of a bottle, and a relatively hard head, said head comprising an annular gripping member having a shoulder at the lower end thereof for engagement with the upper surface of the top of said metal cap and an interior wall of a complementary shape to said polygonal crown, a plurality of teeth extending inwardly from the interior wall of said annular gripping member, said crown extending upwardly into the bore of said gripping member and said teeth being embedded in said crown.

6. A closure for the neck of a bottle comprising a relatively soft stopper having an axial extension, an outstanding annular flange at the upper end of said extension, and a hollow polygonal crown above said flange, a securing member comprising a metal cap having a top, a hole in said top for receiving said crown, a peripherally extending side wall depending from said top and extending downwardly past said flange, means for reducing the diameter of the lower part of said side wall to thereby lock said closure under the bead at the top of the neck of a bottle, and a polystyrene head, said head comprising an annular gripping member having a shoulder at the lower end thereof for engagement with the upper surface of the top of said metal cap and an interior wall of a complementary shape to said polygonal crown, a plurality of teeth extending inwardly from the interior wall of said annular gripping member, said crown extending upwardly into the bore of said gripping member and said teeth being embedded in said crown.

7. A closure for the neck of a bottle comprising a relatively soft stopper having an axial extension, an outstanding annular flange at the upper end of said extension, and a hollow polygonal crown above said flange, a securing member comprising a metal cap having a top,

a hole in said top for receiving said crown, a peripherally extending side wall depending from said top and extending downwardly past said flange, means for reducing the diameter of the lower part of said side wall to thereby lock said closure under the bead at the top of the neck of a bottle, and a relatively hard head, said head comprising an annular gripping member having an interior wall of a complementary shape to said polygonal crown, a plurality of teeth extending inwardly from the interior wall of said annular gripping member, said crown extending upwardly into the bore of said gripping member and said teeth being embedded in said crown.

8. A closure for the neck of a bottle comprising a relatively soft stopper having an axial extension, and a crown above said extension, a securing member comprising a metal cap having a top, a hole in said top for receiving said crown, a peripherally extending side wall depending from said top and extending downwardly, means for reducing the diameter of the lower part of said side wall to thereby lock said closure under the bead at the top of the neck of a bottle, and a relatively hard head, said head comprising an annular gripping member, a plurality of teeth extending inwardly from the interior wall of said annular gripping member, said crown extending upwardly into the bore of said gripping member and said teeth being embedded in said crown.

9. The closure of claim 8, and means for preventing rotation of said head on said crown.

10. A closure for the neck of a bottle comprising a relatively soft stopper having an axial extension, and a crown above said extension, a securing member comprising metal cap having a top, a hole in said top receiving said crown, a peripherally extending side wall depending from said top and extending downwardly, means for reducing the diameter of the lower part of said side wall to thereby lock said closure under the bead at the top of the neck of a bottle, and a relatively hard head above said securing member, said head comprising a gripping member having a bore receiving said crown, and means for preventing relative axial and rotational movement between said head and stopper.
